UNITED STATES PATENT OFFICE

HOWARD J. FERRIS, OF HARVARD, ILLINOIS, ASSIGNOR TO HUNT, HELM, FERRIS & COMPANY, OF HARVARD, ILLINOIS, A CORPORATION OF ILLINOIS

HAY CARRIER

Application filed November 8, 1929. Serial No. 405,662.

My invention relates to hay carriers of the type employing a flexible element by which the elevation of sling-elevating sheaves is controlled, and a clamping mechanism operating to clamp the element when the sheaves are elevated to the desired height.

5 My object is to provide improvements in hay carriers as hitherto provided to the end that the flexible element may be of relative 10 inexpensive construction and of relatively light weight and be effectually clamped with the minimum of wear at the same point repeatedly in the maximum elevation of the load supported by the sheaves, or at any other 15 point along the element in the raising of the load short of the maximum height.

I have chosen to illustrate my improvement 20 in a carrier the parts of which, except for the flexible element by which the elevating of the load is effected, are the same as that disclosed in United States Letters Patent No. 1,207,285 granted December 5, 1916, and therefore a 25 brief description only of the general features of the hay carrier shown will suffice.

25 Referring to the accompanying drawings: Figure 1 is a view in side elevation of my improved hay carrier, one of the sling ropes being removed.

Figure 1^a is a detail of one of the sections 30 of the flexible element by means of which the sling-hoisting sheaves are raised and lowered.

Figure 2 is a view in end elevation of the carrier taken from the right-hand end of Fig. 1 and showing both sling ropes in place.

35 Figure 3 is a section taken at the irregular line 3—3 on Fig. 1 and viewed in the direction of the arrows.

Figure 4 is a view in side elevation, with 40 certain parts in section, of the carrier illustrating the parts in a position in which the flexible element is clamped.

Figure 5 is a plan view of the removable and rotatable carrier head forming an element of the carrier.

45 Figure 6 is a view in side elevation of the sheave which supports the flexible element together with the connected parts, the clamping means for said element being shown in section; and

50 Figure 7, a section taken at the line 7—7

on Figure 1 and viewed in the direction of the arrows.

In the construction shown, 8 represents the track positioned above the place to which the hay is to be discharged and commonly provided adjacent the roof of a hay barn and extending lengthwise thereof.

55 Mounted to travel along the track 8 is a trolley, or traveler-casting, 9 equipped with wheels 10 at which it is supported on the track, the latter being provided with an abutment block 11 adapted to be secured in any desirable position along the track and located directly above the place where the hay is to be elevated by the carrier and thence 60 moved above the location at which it is to be dumped.

65 Rotatably mounted on the trolley 9 is a circular head 12 by which all of the parts hereinafter described are supported. Pivoted on the head 12 by the horizontal pivoting means 13 is a frame 14 between the side members of which a sheave 15 is pivoted as indicated at 16. To one of the side members of the frame 14 a clamp element 17 in the 70 form of a lever is pivoted at 18 and is adapted to cooperate with the flexible element represented generally at 19 and hereinafter fully described, which extends over the sheave 15.

75 The clamp 17 is provided with a segmental rack 20 which meshes with a segmental rack 21 on a bell crank lever 22 fulcrumed at 23 on the frame 14. The bell crank 22 is pivotally connected at 24 with a link 25 which in turn is pivotally connected at 26 with the 80 lower end of a trip lever 27 fulcrumed at a horizontal pivot 28 on the head 12. The lever 27 is provided with two spaced apart upwardly extending projections 29 and 30 adapted in the rocking of the lever 27 in opposite directions to alternately cooperate with the abutment 11. The lever 27 has rigid therewith a hook 31 to which one end of the flexible element 19 is connected as shown in Fig. 2 whereby the weight of the load on the 85 hay carrier is exerted against the lever 27 tending to rock it in a direction for swinging the clamp 17 in clockwise direction in Fig. 4.

90 The mechanism shown also comprises 95 means for releasably maintaining the rope 100

clamp 17 in the released position shown in Fig. 1, these means comprising a lever 32 fulcrumed by a horizontal pivot 33 on the head 12. The lever 32 is provided with an upwardly extending projection 34 which, when the lever 27 extends in the released position shown in Fig. 1, projects beneath a shoulder 35 on the lever 27 and holds these parts in the position just referred to, a coil spring 36 tending at all times to rotate the lever 32 in counter-clockwise direction in Fig. 3. The lever 32 is adapted for connection at 37 with a hand rope for releasing the lever 27 under manual control. The lever 32 is pivotally connected at the opposite side of the pivot 33, as indicated at 38, with the upper end of a push rod 39 the lower end of which is provided with a foot 40 whereby the lever 27 is automatically released when the load carried by the carrier is lifted to the maximum height.

The form of carrier described is particularly intended for handling hay in slings and to this end a pair of sheaves 41 and 42 are hung upon the flexible element 19 as shown in Fig. 2, the frames 43 and 44 in which these sheaves are journalled being provided with hooks 45 and 46, respectively, adapted to be hooked over the sling in which the hay to be lifted is located.

A general description of the operation of the mechanism in so far as it has been described is as follows: Assuming the parts to be in the position shown in Fig. 1 in which position the rope clamp 17 is in inoperating position, and held in this position by the projection 34 of the lever 32, the load is lifted by pulling on the flexible element 19. Assuming that it is desired the load be lifted to the maximum height the operator continues to pull on the element 19 until the sheaves 41 and 42 in engaging the foot 40 rock the lever 32 to the position shown in Fig. 3 whereupon the weight of the load on the lever 27 causes this lever to rotate and force the clamp 17 into clamping position (Fig. 4). During the lifting of the load the carrier is prevented from moving to the left in Fig. 1 because of the engagement of the projection 30 with the abutment 11. Upon the release of the lever 27 as above stated the projection 30 moves to a position below this abutment (Fig. 4) thereby permitting the carrier to be shifted to the left in Fig. 4, by drawing on the flexible element 19. In practice the sling which supports the load is so constructed that by drawing on a rope connected therewith the sling is opened to discharge the load. The carrier is then returned to the point of loading, as for example by pulling on the sling releasing rope. In the movement of the carrier to the position just stated the projection 29 on the lever 27 engages the abutment 11 which causes the lever 27 to rock in counter-clockwise direction in Fig. 4 to the position

shown in Fig. 1 with the result of moving the clamp 17 to inoperating position. The projection 34 on the lever 32 is projected by the spring 36 beneath the portion 35 of the lever 27 thereby locking the lever in clamp-released position. The flexible element 19 may then be paid out to lower the sling-supporting structure carried thereby and comprising the sheaves 41 and 42 to engage with another load to be lifted.

The provision of the connection of a rope to the lever 32 at 37 is to permit the operator in the raising of the load to any height short of the maximum height, to trip the lever 27 for rendering the clamp 17 operative to support the load and withdraw the projection 35 from engagement with the abutment 11.

Referring now to the particular illustrated construction of the flexible element 19, it comprises a section 47 of braided wire cable which at the maximum height of elevation of the load extends into engagement with the sheaves 41 and 42 and over the sheave 15, the outer end of this section being provided with an abutment portion 48 having an eye 49. The element 19 also comprises a section 50 of fiber rope shown as connected at one end with a coupler 51 having an eye 52. The sections 47 and 50 are flexibly connected together as by means of a link 53 extending through the eyes 49 and 52.

The cable section 47 is of such small diameter that it cannot be engaged by the clamp 17 when the latter is swung to the clamping position shown in Figs. 4 and 6. The abutment 48 is of such diameter that it cannot pass between the sheave 15 and the clamp 17 when the latter is in clamping position; and the rope section 50 is of such diameter that it will become clamped between the clamp 17 and the sheave 15 when the clamp 17 is in clamping position.

The section 47 is of such length that when the load is lifted to its maximum height the abutment 48 will extend in a position relative to the clamp 17 substantially as shown in Fig. 1. Therefore, as soon as the lever 27 is released for movement to the position shown in Fig. 4, by the raising of the arm 39, the flexible element 19 will pay out a relatively short distance to the point where the abutment 48 will engage the end of the clamp for supporting the load.

The clamping of the element 19 upon the release of the trip mechanism by the rope connected with the lever 32, will occur at the rope section 50 thereof.

It will, therefore, be understood that I have provided a form of flexible element which is peculiarly adapted to resist wear. The greatest wear occurs in a construction of this general character at the point of gripping the flexible element under the action of the automatic latch releasing means. By providing the abutment 48 for cooperating with

the clamp in the automatic releasing operation referred to undue wear and resultant impairment of the structure, is avoided. At the same time I provide for the utilization of a fiber rope constituting a large part of the element 19 and which is the part at which the element is clamped in the manual release of the tripping mechanism at any desired point short of the maximum height to which the load may be elevated. As the gripping of the rope section 50 under manual control as stated rarely, if ever, occurs at the same point, the advantages resulting from the use of such a rope section are availed of, without objectionable wear of this section.

While I have illustrated and described a particular construction embodying my invention, I do not wish to be understood as intending to limit it thereto, as the same may be variously modified and altered without departing from the spirit of my invention.

What I claim as new, and desire to secure by Letters Patent, is:

1. In combination, a track, a carriage movable thereon, a trip block on said track, a trip member cooperating with said block, sling pulleys, clamping mechanism, and a composite flexible member for controlling the elevation of said pulleys and comprising a section of fiber rope, a section of metal cable and an abutment adjacent the outer end of said metal cable section and adapted to engage said clamping mechanism in the elevated position of said pulleys, said metal cable section being of such diameter that it cannot be clamped by said clamping mechanism and said rope section being of such diameter that it can be clamped by said clamping mechanism.

2. In combination, a track, a carriage movable thereon, a trip block on said track, a trip member cooperating with said block, sling pulleys, clamping mechanism, and a composite flexible member for controlling the elevation of said pulleys and comprising a section of fiber rope, a section of metal cable and a connection between said sections having a portion forming an abutment adapted to engage said clamping mechanism in the elevated position of said pulleys, said metal cable section being of such diameter that it cannot be clamped by said clamping mechanism and said rope section being of such diameter that it can be clamped by said clamping mechanism.

55 HOWARD J. FERRIS.
